UNITED STATES PATENT OFFICE.

LEE S. ANDERSON, OF DETROIT, MICHIGAN.

DEVICE FOR TURNING SHEET-MUSIC.

1,328,976.

Specification of Letters Patent. Patented Jan. 27, 1920.

Application filed September 15, 1919. Serial No. 323,690.

To all whom it may concern:

Be it known that I, LEE S. ANDERSON, a citizen of the Dominion of Canada, subject of the King of Great Britain, residing at 5 Detroit, county of Wayne, State of Michigan, have invented a certain new and useful Improvement in Devices for Turning Sheet-Music, and declare the following to be a full, clear, and exact description of the same, 10 such as will enable others skilled in the art to which it pertains to make and use the same, reference being had to the accompanying drawings, which form a part of this specification.

15 My invention relates to a device for turning sheet music. It is particularly designed for use in connection with a piano or organ, or other musical instrument having an upright music stand. The device is operated 20 by foot from a pedal and is designed to allow the musician to be free at all times. The device as here shown is illustrated in conjunction with the music rack of a piano or organ. It is understood, however, that 25 the device is not claimed merely for use in conjunction with such instrument.

In the drawings,

Figure 1, is a front elevation of the music rack showing the device attached thereto. 30 Fig. 2 is a rear elevation of the music rack showing the device attached thereto.

Fig. 3 is a cross-section partly broken away, taken on line III—III of Fig. 1.

Fig. 4 is an enlarged elevation of guide 35 plate shown in Fig. 1.

Fig. 5 is a cross-section taken on the line V—V of Fig. 3.

The music rack 2 is recessed longitudinally, as shown at 3. This recess is 40 formed so as to provide a path or way for the longitudinal movement of guide plate 1, the outer surface of such guide plate being flush with the surface of the music rack. The guide plate is held in place by means of 45 a strip or clip 3^a. Affixed to the rear of the guide plate is a rack extending longitudinally thereof at approximately the central portion designated as 4. This rack is designed to mesh with a pinion 5 carried at 50 the upper end of the shaft 6, said shaft being disposed in bearings 7, 7. The lower end of this shaft is provided with a bevel gear 8 which meshes at right angles with the bevel gear 9. Bevel gear 9 has at the oppo-

site end the shaft 10, upon which it is 55 mounted, a foot pedal 11. This foot pedal 11 is so disposed as to be easily operated by the musician. This particular arrangement of bevel gears and shafts might be varied to meet particular designs of instrument 60 with which the attachment is used. It will be seen that the operation of the foot pedal 11 serves to permit motion from the shafts and gears heretofore described to guide plate 1 as the pinion 5 meshes with the rack 65 4 carried by said guide plate; therefore the operation of the foot pedal a predetermined distance will move the guide plate a predetermined distance within the recess 3 of the music rack. The face of said guide 70 plate 1 is provided with a series of racks extending longitudinally thereof in successive parallel planes designated in Fig. 4, as 12, 13 and 14. Alternating with these racks and of slightly greater altitude, the 75 ends of which somewhat overlap the ends of the racks, are guide rods 15, 16, and 17 for purposes hereafter described.

There is provided on the front of the music rack brackets 18 and 18^a carrying 80 shaft 19 upon which shaft are freely mounted pinions 20, 21, and 22. These pinions are held in spaced relationship one from the other by means of bushing or pinion hubs and are designed to mesh with 85 racks 12, 13 and 14 respectively. It will be observed that the music rail is cut away in the rear of such pinions, as at 23, so as to permit the engagement of the pinions with the racks carried by the guide plate. Affixed 90 radially to pinions 20, 21, and 22 are arms 24, 25 and 26. These arms are offset at their outer extremities so that the extremities will lie in substantially the same horizontal plane and will overhang the sheet music 95 carried on the rail of the rack. These arms are likewise of varying lengths so there will be no conflict in the individual movement thereof. The outer extremities of these radially-extending arms are provided with 100 clips 24^a, 25^a and 26^a adapted to grip the sheets of music intended to be operated by this device. It is apparent that the number of pinions and therefore the number of radially-extending arms may be increased, 105 if so desired. Carried by pinions 20, 21, and 22 are stops 27, 28 and 29 which are adapted to be engaged by the guide rods 15,

A. F. POOLE.

GEAR SHIFT FOR CROSS ACTUATORS.

APPLICATION FILED JULY 8, 1918.

1,329,014.

Patented Jan. 27, 1920.

2 SHEETS—SHEET 2.

UNITED STATES PATENT OFFICE.

ARTHUR F. POOLE, OF KENILWORTH, ILLINOIS, ASSIGNOR TO THE WAHL COMPANY, OF WILMINGTON, DELAWARE, A CORPORATION OF DELAWARE.

GEAR-SHIFT FOR CROSS-ACTUATORS.

1,329,014.

Specification of Letters Patent. Patented Jan. 27, 1920.

Application filed July 8, 1918. Serial No. 243,995.

To all whom it may concern:

Be it known that I, ARTHUR F. POOLE, a citizen of the United States, residing at Kenilworth, in the county of Cook and State 5 of Illinois, have invented certain new and useful Improvements in Gear-Shifts for Cross-Actuators, of which the following is a specification.

My invention is an improvement in calculating machines and is shown particularly 10 applied to the Wahl crossfooting machine now in wide commercial use and illustrated in the patent to me, No. 1,198,050, September 12, 1916, and also in my copending application Ser. No. 709,010, filed July 12, 15 1912.

My present invention is an improvement in the gear shift device shown in my cited copending application and has for its object 20 the making of said gear shift device simpler in order to accommodate itself to a certain class of calculations for which all the functions present in the gear shift device shown in my cited application are not required. More specifically in said cited application are shown a vertical actuator and a cross actuator. The vertical actuator may be thrown in any one of three conditions, 25 viz., addition, subtraction, or disconnect. The cross actuator may similarly occupy any one of three positions, viz., addition, subtraction or disconnect. The cross actuator may be controlled in two distinct ways, first 30 by an automatic control actuated by certain cams mounted on the typewriter carriage, and second by a manual control actuated by a certain lever associated with the cross actuator. Either the manual or the automatic control may place the cross actuator in any 35 of its three conditions and in addition there is provided a shift lever for the purpose of determining whether the cross actuator should be under manual or automatic control.

It frequently happens that a crossfooting machine is sold to be used steadily on a pre-determined program of work, which program is set up on the cams of the typewriter carriage. The manual control therefore becomes superfluous and it is one of the objects of my present invention to so modify and change the gear shift mechanism shown in my cited application that this manual control will be absent from the machine and its place be taken in part by the

lever formerly used to shift from automatic to manual control.

My invention will be best understood by reference to the following figures, of which

Figure 1 is a front elevation of a Wahl 60 crossfooting machine equipped with my improved gear shift;

Figs. 2 and 3 are perspective views of my improved gear shift, and

Fig. 4 is a top view of a part of the mech- 65 anism.

Similar reference numerals refer to like parts in all the figures.

The Wahl crossfooting machine is mounted on a Remington typewriter 10, which is 70 provided with digit keys 11, tabulating keys 12 and alphabetical keys (not shown). A pull rod 13 extends from each of the digit keys 11 to the vertical actuator 14, which contains the customary Wahl mechanism, 75 having for its object the translation of the vertical motion of the pull rod 13 into a differential rotation of a vertical master wheel 15 in a direction determined by the position of the vertical gear shift rod 16. By connections thoroughly described in my issued Patent No. 1,198,050, September 12, 1916, the vertical actuator 14 is connected to a cross actuator 17, which is provided with the cross master wheel 18, which upon motion of any 80 85 of the digit keys 11, revolves a differential amount, determined by the position of the cross gear shift rod 19. The precise mechanism by which the reciprocating motion of the digit keys 11 is transformed into differential motion of the master wheels 15 and 18 need not be described in this place, since the Wahl mechanism by which these results are accomplished is very thoroughly described in a number of issued patents, in 90 95 particular my Patent No. 1,198,050, just referred to, and also Patent No. 1,148,733, August 3, 1915. It will be sufficient for an understanding of my present invention to assume that the reciprocating motion of any 100 of the digit keys is translated in a differential rotation of the master wheels 15 and 18, as determined by the position of the gear shift rods 16 and 19. A traveling truck 20 is mounted on the framework 10 of the typewriter and serves to support the vertical totalizers 21, 22 and 23, which are held in their position by suitable latches 24, which engage the teeth of a rack 25 rigid with the truck 20. The truck 20 is slidably mounted 105

110

in the framework of the machine and is attached to the carriage (not shown) of the typewriter by brackets 26 and 27, which serve to communicate the step-by-step motion to the left of the typewriter carriage to the truck 20. As the truck 20 moves step by step, the totalizers 21, 22 and 23 are moved step by step over the vertical master wheel 15, and numbers are inserted in these totalizers one digit at a time, in the well known manner.

Extending from the right of the vertical actuator 14 is the cross casting 28, which is provided with suitable ways, in which reciprocates the cross truck 29, normally held to the right by a spring 30 extending over a roller 31 in said casting. The cross truck 29 serves as a support for the cross totalizer 32 and is also provided with a pick-up beam 33, which is adapted to be picked up successively by the vertical totalizers 21, 22 and 23, and thus move the cross truck 29 in synchronism with the master wheel 20 during the time the several vertical totalizers are in engagement with the vertical master wheel 15. Numbers may thus be inserted simultaneously into any of the vertical totalizers 21, 22 and 23 and the cross totalizer 32.

As before noted, the direction of rotation 30 of the vertical master wheel 15 is determined by the position of the vertical gear shift rod 16, said rod having three positions, corresponding to an addition, subtraction and disconnect position respectively. The mechanism connected with the gear shift rod 16 is described in my copending application Serial No. 709,010, and need not further be described in this place. The direction of rotation of the cross master wheel 18 is determined by the position of the cross gear shift rod 19, which is slidably mounted in the framework and is controlled by a lever 34 pivoted in the framework on a stud 35. The upper end of the lever 34 is provided 40 with a stud screw 36, pivoted to which is a link 37, which is pivoted to the crank arm 38, mounted on a shaft 39, rotatably mounted in the framework of the machine. The rear end of the shaft 39 is provided with a 45 crank arm 40, having a pin 41 therein, which is engaged by a V-shaped slot 42 in a floating cam plate 43. The floating cam plate 43 may be moved from either of two points: First, from a pin 44, which is constrained to 50 move in a horizontal line by a plate (not shown), and second, from a pin 45 in the upper end of the cam plate 43. The pin 45 is controlled from either of two sources: First, by the plates 46, which are pivoted 55 to the upper end of a lever 47 rigid to a shaft 48 rotatably mounted in the framework of the machine and having on its forward end a crank arm 49, on which is mounted a roller 50, which is engaged and depressed by cams 51 and 52, mounted on

the vertical totalizers 22 and 23. By providing cams 51 and 52 of various heights, it is possible to predetermine any of the three possible positions of the cross gear shift rods 19. It will be noticed that the vertical totalizer 21 is not provided with any cam and when said totalizer is in engagement with the vertical master wheel 15 the position of the gear shift rod 19 is determined by the tension spring 53, extending 70 from a stud 54 in the framework to the lever 47. The lever 47 is provided with an arm 55, which is adapted to contact with a pin 56 mounted in a lever 57, rotatably mounted on a stud 58 in the framework. 80

When the spring 53 brings the lever 47 into a position determined by the contact of the arm 55 with the stud 56, the cross gear shift rod 19 is in its position determining addition for the cross master wheel 18. 85 When the roller 50 is depressed by one of the cams 51 or 52, it may be either depressed all of the way, thereby determining the subtraction position of the gear shift rod 19, or it may be depressed only a part of the 90 way, thereby determining a disconnect position of the gear shift rod 19.

From the preceding it will be apparent how the first method of controlling the pin 45 in the floating cam plate 43 is operated, 95 that is, how the position of the roller 50 may determine any one of the three positions of the cross gear shift rod 19.

I shall now describe the second means of determining the position of the pin 45 in 100 the cam plate 43. Referring to Figs. 1, 2 and 3, it will be observed that the machine is provided with a shift handle 60, pivoted at a stud 59 on the frame work and provided with a link 61, which serves to connect the handle 60 with the lever 57 previously referred to. The lever 57 is provided with a pin 62, which engages a slot 63 in a rocker 64, pivoted on a stud 65 in the framework of the machine and provided with a pin 66 105 engaging a slot 67 in the plate 46. When the parts are in the position shown in Fig. 2 that is, when the machine is under automatic control, the pin 66, by reason of its engagement with the slot 67, serves to maintain the 110 plate 46 in contact with the pin 45, thus determining that the cross gear shift rod 19 shall be under the automatic control of the roller 50. When, however, the handle 60 is shifted to the position shown in Fig. 2, it 115 will be observed that the plate 46 is withdrawn from its contact with the pin 45, and that the position of said pin is determined by its engagement with a notch 68 in the upper part of the rocker 64. 120

The position of the notch 68 is such that the pin 45 is always thrown into position determining the disconnect position of the gear shift rod 19, so that the lever 60 is in effect a disconnect lever for the cross actu- 130

ator, thereby enabling said actuator to be thrown into a disconnect position without affecting the setting of the vertical actuator.

It is, of course, obvious that this throwing of the cross actuator into the disconnect position is not necessary, but that the handle 60 may throw the cross actuator into either subtraction or addition, since this obviously depends on the location of the notch 68. However, as will be hereinafter explained, I prefer to throw the cross actuator into a disconnect position when the lever 60 is operated.

In order to correct errors on my improved machine it is desirable to reinsert a number in the opposite direction from that in which an erroneous number was inserted, thereby canceling the erroneous insertion. From the preceding it is obvious that the vertical actuator may be in any one of three possible positions, that is, addition, disconnect or subtraction, and that the cross actuator may similarly be in any of three possible conditions, viz., addition, disconnect or subtraction. It therefore becomes highly desirable to have a single lever which, when actuated, will throw both the cross and vertical actuators into the reverse of their former condition. In my improved machine I have provided a lever of this kind at 69. Said lever is rotatably mounted on a stud 70 in the framework and is connected by a link 71 to a bell crank lever 72, rotatably mounted on a stud 73 rigid in the framework. A pair of links 74 and 75 serves to connect the bell crank 72 with a pin 76 in the vertical cam plate 77 and the pin 44 in the floating cam plate 43 for the cross actuator. The motion of the handle 69 is such that it will move the pins 76 and 44 through half the angle subtended from the pin 45 by the slot 42. This slot is so shaped that moving the cam plate 43 through half of this angle will throw the pin 41 into the reverse of its former condition. That is, if said pin stood in a position corresponding to the addition position of the gear shift rod 19, said pin will be moved to a position determining a subtraction position of the gear shift rod 19, and vice versa. Since the disconnect position is intermediate between the addition and subtraction positions, the reverse of a disconnect position is a second disconnect position, so that if either the vertical or horizontal actuator is in its disconnect

position it will remain in said position after the lever 69 has been operated.

Many changes and modifications may be made in the precise mechanism herein shown without departing from the spirit of my invention, since I claim:

1. In a calculating machine, the combination of a totalizer, an actuator adapted to insert numerals therein *seriatim*, an automatic control for said actuator and a manual control for said actuator, said manual control being adapted to disconnect said actuator from said automatic control and bring said actuator into a predetermined condition. 65

2. In a calculating machine, the combination of a gear shift, a traveling member, means actuated by said traveling member for controlling said gear shift, and a second means of controlling said gear shift to bring said gear shift to a determined position. 75

3. In a calculating machine, the combination of a gear shift, an automatic control for said gear shift, and means for rendering said automatic control ineffective on said gear shift and simultaneously bringing said gear shift to a predetermined position. 80

4. In a calculating machine, the combination of a gear shift determining the direction in which numbers are entered in said machine, a floating lever whose position determines the position of said gear shift, a traveling member, means operated by said traveling member to control said floating lever, and manual means to disconnect said automatic control from said floating lever and bring one part of said floating lever to a predetermined position. 85

5. In a calculating machine, the combination of a gear shift determining the direction in which numbers are entered in said machine, a floating lever whose position determines the position of said gear shift, a traveling member, means operated by said traveling member to control said floating lever, manual means to disconnect said automatic control from said floating lever and bring one part of said floating lever to a predetermined position, and means to control the position of a second point in said floating lever. 95 100 105

In witness whereof I have hereunto subscribed my name,

ARTHUR F. POOLE.
